UNITED STATES PATENT OFFICE.

HERMAN L. HOHLFELD, OF PHILADELPHIA, PENNSYLVANIA.

SUSPENSION-COUCH.

942,259.

Specification of Letters Patent.

Patented Dec. 7, 1909.

Application filed June 27, 1908. Serial No. 440,736.

To all whom it may concern:

Be it known that I, HERMAN L. HOHLFELD, a citizen of the United States, and a resident of the city of Philadelphia, State of Pennsylvania, have invented certain new and useful Improvements in Suspension-Couches, of which the following is a full, clear, and complete disclosure, reference being had to the accompanying drawings, forming part of this specification.

The main objects of this invention are to provide a suspension couch of simple and attractive design, which may be constructed cheaply, and which will be strong, durable and comfortable in use; to provide a couch which may be conveniently taken apart, re-assembled and adjusted; and to provide other improvements, all of which will appear in the following specification.

In the drawings Figure 1 is a side elevation of a suspension couch constructed in accordance with this invention, the central portion of the couch being broken away; Fig. 2 an enlarged bottom plan view of one end of the same; Fig. 3 a longitudinal vertical section of one end of the same and Fig. 4 an enlarged fragmentary bottom plan view of the same.

Referring to the drawings, the couch comprises a substantially rectangular main frame consisting of side bars 1 and end bars 2; across and over which is stretched a cover 3 of canvas or other suitable material, the edges of which are brought downwardly around the outside edges of the frame, and folded inwardly upon the under side thereof. The edges of the cover 3 are provided with pockets 4 within which are loosely placed rods 5 and eyelets 6 are provided passing through the two sides of the pockets and adjacent the inside of the rods. Lacings 7 which extend across and upon the under side of the frame, through the eyelets of the cover between the opposite edges of the cover, stretch the same tightly upon the frame.

A woven wire spring 8 is stretched across the frame beneath and adjacent the cover 3. The end edges of this woven spring are secured between the folds of metal binders 9 by means of rivets 10 extending through the sides of the binders and the binders are fastened into recesses provided therefor in the upper inner edges of the end bars by nails 11 or other suitable means.

The side edges and central part of the woven spring are stiffened by a plurality of longitudinal spiral wires 12, and the side edges are further stiffened by means of longitudinal straight metal wires or rods 13 which run through the spiral wires 12. The ends of the rods 13 are bent to form hooks 14 which engage in eyes in the inner ends of flat bars 15 and the outer ends of the bars are secured between the folds of the metal binders 9. The rods 13 are also supported in screw eyes 16 fastened into the inner edges of the side bars of the frame. The ends of the wires of the spring 8 are coiled around transverse rods 17 which are held in binders 9 by nails 11.

For suspending the couch, a cloth 18 is provided at each end thereof, the end edges of which are preferably folded and stitched to form transverse pockets 19 and 20, through which extend spreaders 21 and 22 respectively. The inner end of the cloths 18 are secured upon the under side and adjacent the ends respectively of the frame by means of cleats 23 which pass through the cloths 18 as at 24 and around the outside of the inner portions of the cloth forming the pockets 19, and the cleats are fastened to the end bars of the frame by means of screws 25 or other devices. By this arrangement, the cleats 23 and spreaders 21 serve the double function of holding both the cover 3 and the cloths 18 in position upon the frame.

The outer ends of the cloths 18 are provided with apertures 26 upon the inner sides of the spreaders 22, through which are passed clue cords 27, the outer ends of which are secured to a ring 28, whereby the couch is suspended. Instead of apertures in the cloths 18 adjacent the ends of the spreaders 22, I preferably use clips 29, having integral therewith prongs 30 passing through the cloths 18 and the spreaders 22 and riveted in place to hold the edges of the cloths in position. These clips are curved to fit around the cloths on the spreaders, and are provided with eyes 31 which serve to hold the inner ends of the outer clue cord in position. The edges of the couch may be finished with a valance 32 which is preferably stitched or otherwise fastened to the cover 3.

Although I have shown only one form in which this invention may be constructed, yet it is obvious that many changes might be made in the construction herein illustrated,

within the scope of the appended claims, without departing from the spirit of this invention or sacrificing any of the advantages thereof.

5 Having thus fully described my invention, I claim and desire to secure by Letters Patent of the United States:

1. A suspension couch comprising a frame, a cloth for suspending said frame having a 10 pocket in one edge thereof, and a spreader extending through said pocket and secured to said frame for holding said cloth in position.

2. A suspension couch comprising a frame, 15 a cloth cover for said frame over the upper side thereof, a spring mattress secured to said frame beneath said cover, a spreader, means carried by said spreader to suspend said couch, and means to hold said spreader upon said frame, said means serving also to hold said cover in place.

3. A suspension couch comprising a substantially rectangular frame, a cover extending over the upper side of said frame and 25 around the outside edges thereof, lacing upon the other side of said frame to hold said cover in position, a spreader upon the under side of said frame and outside of said cover, means to secure said spreader to said frame, and means carried by said spreader for supporting the couch.

4. A suspension couch comprising a frame, a cover extending across the upper side of 30 said frame and around one edge of and extending inwardly upon the under side thereof, a spreader upon the under side of said frame and outside of said cover, a cleat passing through said cover and around said spreader securing said spreader to said frame, and means carried by said spreader to support said couch.

5. A suspension couch comprising a frame, a cover across the upper side of said frame, and around the under edge thereof, a 45 spreader secured to the under side of said frame and outside of said cover, a cloth carried by said spreader for suspending said couch, said cloth having a spreader upon the outer end thereof, and clue cords connected 50 to said last mentioned spreader.

6. A suspension couch comprising a frame, a cloth for suspending said frame, having a 55 pocket in one edge thereof, and a spreader extending through said pocket and rigidly secured to said frame for holding said cloth in position.

7. A suspension couch comprising a frame, a cloth for suspending said frame having a 60 pocket in one edge thereof, and located upon the under side of said frame, and a spreader extending through said pocket and rigidly secured to said frame for holding said cloth in position.

8. A suspension couch comprising a frame, 65 means for suspending said frame, and a

spreader rigidly secured to said frame for connecting said means to said frame.

9. A suspension couch comprising a frame, means for suspending said frame, and a spreader rigidly secured to the under side 70 of said frame and connecting said means to said frame.

10. A suspension couch comprising a frame, a cover for said frame, means for supporting said frame, and a spreader secured to said frame and holding said cover and said suspending means in position.

11. A suspension couch comprising a frame, a cover for said frame, means for supporting said frame, and a spreader rigidly secured to the under side of said frame 80 and holding said cover and said suspending means in position.

12. A suspension couch comprising a frame, a cover for said frame, a spring mattress secured to said frame beneath said cover, a spreader, means carried by said spreader to suspend said couch, and means connecting said spreader to said frame, said latter means serving also to hold said cover 90 in place.

13. A suspension couch comprising a frame, a cover extending over one side of said frame and around one edge thereof, a spreader rigidly secured to the other side 95 of said frame, and outside of said cover, and holding said cover in place, and means carried by said spreader for supporting said couch.

14. A suspension couch comprising a frame, a cover extending over the upper side of said frame and around one edge thereof, a spreader rigidly secured to the under side of said frame and outside of said cover, holding said cover in place, and 105 means carried by said spreader for supporting said couch.

15. A suspension couch comprising a frame, a cloth for suspending said frame, having a pocket in one edge thereof, a 110 spreader extending through said pocket, and a cleat extending through said cloth and around said spreader and rigidly secured to said frame for holding said cloth in position.

16. A suspension couch comprising a frame, a cloth for suspending said frame having a pocket in one edge thereof, a spreader extending through said pocket, and a cleat extending through the two thicknesses of cloth forming said pocket and around said spreader and rigidly secured to said frame, for holding said cloth in position.

17. A suspension couch comprising a frame, a cloth for suspending said frame from the upper side thereof, a spring mattress secured to said frame beneath said cover, a spreader, means carried by said cover to suspend said couch, and means 125

130

rigidly connecting said spreader to said frame, said latter means serving also to hold said cover in place.

18. A suspension couch comprising a frame, a spring mattress connected to said frame, a cover extending over both sides of said frame and over-lapping both sides of said mattress, a spreader rigidly connected to said frame and holding said cover

in place, and means connected to said spreader for suspending said couch.

In witness whereof I have hereunto set my hand this 23rd day of June 1908.

HERMAN L. HOHLFELD.
